United States Patent

Des. 236,924
Patented Sept. 30, 1975

236,924

PAPER HANDLING STAND

Loren D. Stirling, Pleasanton, Calif., assignor to Xerox
Corporation, Stamford, Conn.

Filed Dec. 3, 1973, Ser. No. 420,830

Term of patent 14 years

Int. Cl. D6—99

U.S. Cl. D6—85

FIG. 1

FIG. 2

FIG. 3

FIG. 6

FIG. 1 is a perspective view of a paper handling stand showing my new design;

FIG. 2 is an elevational view taken from one side thereof;

FIG. 3 is an end elevational view thereof;

FIG. 4 is an elevational view taken from the side opposite of that shown in FIG. 2;

FIG. 5 is an end elevational view taken from the end opposite of that shown in FIG. 3; and

FIG. 6 is a top plan view thereof.

I claim:

The ornamental design for a paper handling stand, as shown.
